UNITED STATES PATENT OFFICE

118,503

DESIGN FOR A STEERING WHEEL

Raymond W. Parriott, Moundsville, W. Va.

Application October 20, 1939, Serial No. 87,776

Term of patent 7 years

To all whom it may concern:

Be it known that I, Raymond W. Parriott, a citizen of the United States, residing at Moundsville, in the county of Marshall and State of West Virginia, have invented a new, original, and ornamental Design for a Steering Wheel, whereof the following is a specification, reference being had to the accompanying drawing, forming part thereof.

In the aforesaid drawing:

Fig. 1 is a top plan view of a steering wheel showing my new design, and

Fig. 2 is a side elevational view thereof.

I claim:

The ornamental design for a steering wheel, as shown.

RAYMOND W. PARRIOTT.
